BY *Robert E. Fair*.

FIG. 2.

UNITED STATES PATENT OFFICE

2,524,003

DEVICE FOR STACKING HAY

David A. Wallace, Detroit, Mich.

Application July 14, 1945, Serial No. 605,111

1 Claim. (Cl. 130—20)

1

This invention relates to apparatus for stacking hay and similar materials.

One of the main objects of the invention is to provide a readily portable crib-like structure into which hay may be deposited and which, when filled or partially filled, may be conveniently removed from the resulting stack and transported to another location for re-use in a similar manner.

Another object of the invention is the provision of a device of this character which is so constructed as to form a stack of predetermined shape having side and end extremities diverging upwardly at an angle with respect to each other.

A further object of the invention is to provide hinged extension panels on opposite sides of a device of this kind for facilitating the formation of stacks of different height.

Other objects of the invention are to provide skid-type runners on a device of this kind for accommodating movement thereof from the location of one stack to the location at which another is to be formed; to provide in a crib-like structure of this kind a pair of gate sections which when closed form one end wall of the structure and which are adapted to swing into an open position in which they are completely out of alignment with the interior or crib for accommodating endwise removal of the crib from the stack of hay deposited therein; to provide resiliently yielding means for connecting the end of the crib opposite from the gate sections to the lateral side walls of the crib which accommodate limited outward deflection of the side walls in order to free them from engagement with the corresponding sides of the stack formed therein, preparatory to removal of the crib from the stack; and to provide a structure of this kind which does not require transversely extending tie members, other than the end walls of the crib, for retaining the lateral side walls thereof in their proper relation.

An illustrative embodiment of the invention is shown in the accompanying drawings, in which:

Fig. 1 is a front end elevational view of a hay stacking crib embodying the invention and illustrating the manner of filling it.

Fig. 2 is a top plan view of the hay stacking crib shown in Fig. 1.

Fig. 3 is a longitudinal side elevational view of the hay stacking crib illustrated in Figs. 1 and 2.

In the form of the invention shown in the drawings, my hay stacker comprises a crib-like structure having spaced lateral side walls 10 and 11, a permanently closed end wall 12 and an opposite end wall which includes gate sections 13 and 14. 55

2

The lateral side walls of the crib comprises lattice construction, each being formed of a plurality of substantially parallel upwardly extending wood slats 15 fixed together at their upper ends and at their intermediate portions by horizontally extending beam members 16 and 17, respectively. The lower ends of the slats 15 of the side walls 10 and 11 are fixed to skid-type runners 18 and 19, respectively, which are adapted to shiftable support the crib upon and in spaced relation from the ground.

The permanent end wall 12 comprises a plurality of spaced, upwardly extending slats 20 which are tied together at their upper and lower ends and at their intermediate portions by horizontal beam members 21. The gate sections 13 and 14 also comprise spaced, upwardly extending slats, designated by the numerals 22 and 23, respectively. The upper and lower ends of the slats of the gate sections are fixed to beam members and each gate section is reinforced by a pair of crossed cleats 25. All of the foregoing wall structures are illustrated as comprising wood but it should be understood that metal or other suitable material may be employed.

The two lateral side walls and the two end walls diverge upwardly and outwardly from each other at a suitable angle to produce a stack having a desired taper. The side walls 10 and 11 are yieldably fixed at their upper and lower portions to the permanent end wall 12 by metal angle brackets 10' which are sufficiently yieldable to accommodate outward flexure of the extremities of the side walls which are located adjacent the gate sections 13 and 14. The gate sections 13 and 14 are pivotally mounted on the side walls 10 and 11, respectively, by hinges 26. The hinges 26 permit the gate sections to be swung out of alignment with the interior of the crib. Latch members 27 on the free edges of the gate sections 13 and 14 serve to releasably hold the gate sections in closed position during filling of the crib to form a stack of hay or the like.

Extension panels 28 and 29 may be pivotally mounted on the upper extremities of the side walls 10 and 11, respectively, by hinges 30 in order to increase the effective height of the crib. The extension panels 38 and 39 may be held in their upright positions by a suitable means such as the bars 31 pivotally mounted at 32 on the upper beam members 17 of the side walls 10 and 11. When the bars 31 are arranged in horizontal alignment, the extension panels may be raised and lowered by pivotal movement on their hinges 30 and when the bars 31 are moved to their upright positions

after the extension panels 28 and 29 are raised, they hold the latter in the position illustrated in Fig. 3.

In operation, the crib may be drawn upon the runners 18 and 19, by a chain 33 attached to the ends of the runners, to any location at which it is desired to form a stack of hay. While the gate sections 13 and 14 are locked in closed position, the interior of the crib, the top and bottom of which are open, may be filled with hay. After the crib is filled, the gate sections 13 and 14 may be pivoted to open position and preferably disposed against the outer sides of the side walls 10 and 11, respectively. The crib may then be removed endwise from the stack of hay or like material formed therein, and shifted to a new location at which it is desired to form another stack. This operation may take place with the extensions 28 and 29 of the side walls 10 and 11 in either their lower or elevated positions. The crib may be filled by hand or by a mechanical hay lifter and loader, generally designated by the numeral 29', such as that illustrated in Fig. 1. In either event the stack is brought to a desired shape and formation without requiring the manual labor necessary to arrange the hay into a stack of desired shape, as in the present conventional practice.

Although but one specific embodiment of the invention is herein shown and described, it will be understood that various changes in the sequence of operations, steps and materials employed may be made without departing from the spirit of the invention.

I claim:

A device for stacking hay and the like comprising a crib-like structure having spaced lateral side and end walls and open unobstructed top and bottom extremities, a runner on the lower edge of each of said side walls extending longitudinally thereof for holding said crib-like structure in spaced relation to the ground and accommodating sled-like movement of said device over the ground, said runners extending continuously throughout

the length of said crib-like structure for preventing outward flow of hay between the ground and said crib-like structure, one of said end walls comprising a pair of gate sections, means pivotally mounting each of said sections at its outer edge on one of said side walls respectively and adapted to accommodate swinging of said sections outwardly with respect to each other to positions out of alignment with the interior of said crib-like structure after the latter is filled for facilitating endwise displacement of said crib-like structure on said runners from the stack of hay formed therein, means for releasably holding said sections in closed position during filling of said crib-like structure, and means connecting the vertical edges of the opposite end wall and the adjacent vertical edges of the side walls comprising a yieldable member for accommodating outward deflection of said side walls about a vertical axis during removal of said crib-like structure for a stack of hay.

DAVID A. WALLACE.
